UNITED STATES PATENT OFFICE.

GEORGE E. GREENE, OF GARDNER, MASSACHUSETTS.

DESIGN FOR A HANDLE FOR DENTAL PLUGGERS.

SPECIFICATION forming part of Design No. 29,560, dated November 1, 1898.

Application filed May 14, 1898. Serial No. 680,747. Term of patent 7 years.

To all whom it may concern:

Be it known that I, GEORGE E. GREENE, a citizen of the United States, residing at Gardner, in the county of Worcester and State of Massachusetts, have invented and produced a new and original Design for a Handle for Dental Pluggers, of which the following is a specification, reference being had to the accompanying drawing, forming a part thereof.

10 The drawing represents a view in elevation of a handle for dental pluggers, showing my new design.

As shown in the drawing, the leading or material feature of my design consists in the 15 shape or contour of the dental-plugger handle. The upper or thick end A of the handle is convex. The portion of the sides lettered B—that is to say, that portion which lies between the points Y and the thick end of the 20 handle—grows gradually thinner from said thick end to the points Y, the opposite lines of the portions B of said sides being straight

and approaching each other at a very slight angle. From the points Y to the points X the opposite lines C of the sides of the handle approach each other at a slightly-greater angle, and at said points X the handle is bent on a curve to one side, as shown, until its end projects at substantially an angle of nearly forty-five degrees. The portion from X to 25 the lower end of the handle is, however, not straight, but curved, as indicated in the drawing, and said portion decreases in thickness from the points X to the lower end.

Having described my invention, what I 30 claim as new, and desire to secure by Letters Patent, is—

The design for a handle for dental pluggers, substantially as herein shown and described.

GEORGE E. GREENE.
